FLOODLIGHT

FIELD

The present invention relates to a floodlight.

BACKGROUND

On worksites such as construction sites, floodlights, one example of which is disclosed in Patent Literature 1, are used.

CITATION LIST

Patent Literature

Patent Literature 1: JP 2014-212025 A

SUMMARY

Technical Problem

Such a floodlight has an operation device that is operated to adjust the state of the light emission of a light emitter unit. When a floodlight having such an operation device in an upper part of the floodlight is placed at a high place, the operation device is hard to reach and is obstructed from being smoothly operated.

The floodlight also has a light source that emits light. Because such a light source becomes heated, a floodlight requires some technology for suppressing excessive heating of the light source.

An object of an aspect of the present invention is to provide a floodlight allowing an operation for adjusting the light emission state to be performed smoothly. An object of an aspect of the present invention is to provide a floodlight capable of suppressing excessive heating of the light source.

Solution to Problem

According to a first aspect of the present invention, provided is a floodlight including: a main-body member that includes a light emitter unit; an arm that is coupled to a coupling mechanism provided to a side face of the main-body member and is pivotable about a rotational axis; and an operation device that is disposed in the coupling mechanism and is operated to adjust the light emission state of the light emitter.

According to a second aspect of the present invention, provided is a floodlight including: a light source; a support member that supports the light source; and a fan that cools the light source by generating an air flow on a surface of the support member. The light source is supported on a front face of the support member and emits light forward with respect to the support member. The fan is disposed rearward of the support member, at a position facing the support member.

Advantageous Effects of Invention

According to an aspect of the present invention, provided is a floodlight allowing an operation for adjusting the light emission state to be performed smoothly. Furthermore, according to an aspect of the present invention, a floodlight capable of suppressing excessive heating of the light source is provided.

2

BRIEF DESCRIPTION OF DRAWINGS

FIG. 1 is a perspective view of a floodlight according to a first embodiment.

5 FIG. 2 is a plan view of the floodlight according to the first embodiment.

FIG. 3 is a sectional view of an operation device according to the first embodiment.

FIG. 4 is a perspective view of a second coupling mechanism according to the first embodiment.

FIG. 5 is a perspective view of the heat-radiating member according to the first embodiment.

FIG. 6 is a perspective view of the floodlight according to the first embodiment, seen from a rear side.

15 FIG. 7 is a perspective view of the floodlight according to the first embodiment, seen from the rear side.

FIG. 8 is a perspective view of the floodlight according to the first embodiment, seen from the rear side.

FIG. 9 is a sectional view of the floodlight according to the first embodiment.

20 FIG. 10 is a functional block diagram illustrating a control device according to the first embodiment.

FIG. 11 is a schematic illustrating how the floodlight according to the first embodiment is used.

FIG. 12 is a perspective view of a floodlight according to a second embodiment.

25 FIG. 13 is a schematic illustrating how the floodlight according to the second embodiment is used.

FIG. 14 is a perspective view of a floodlight according to a third embodiment.

FIG. 15 is a schematic illustrating how the floodlight according to the third embodiment is used.

FIG. 16 is a perspective view of a floodlight according to a fourth embodiment.

FIG. 17 is a plan view of the floodlight according to the fourth embodiment.

30 FIG. 18 is a perspective view of a second coupling mechanism according to the fourth embodiment.

FIG. 19 is a perspective view of a heat-radiating member according to the fourth embodiment.

FIG. 20 is a perspective view of the floodlight according to the fourth embodiment, seen from the rear side.

FIG. 21 is a perspective view of the floodlight according to the fourth embodiment, seen from the rear side.

FIG. 22 is a perspective view of the floodlight according to the fourth embodiment, seen from the rear side.

45 FIG. 23 is a sectional view of the floodlight according to the fourth embodiment.

FIG. 24 is a sectional view of the floodlight according to the fourth embodiment.

FIG. 25 is a perspective view of the floodlight according to the fourth embodiment.

50 FIG. 26 is a functional block diagram illustrating a control device according to the fourth embodiment.

FIG. 27 is a schematic illustrating effects of a fan according to the fourth embodiment.

DESCRIPTION OF EMBODIMENTS

Embodiments of the present invention will now be explained below with reference to some drawings, but the scope of the present invention is not limited to the embodiments. Elements included in the embodiments described below may be combined as appropriate. Furthermore, it is also possible to omit the use of some of these elements.

First Embodiment

65 FIG. 1 is a perspective view of one example of a floodlight 100A according to this embodiment. FIG. 2 is a plan view

of the one example of the floodlight 100A according to this embodiment. The floodlight 100A is used on a worksite such as a construction site. The floodlight 100A emits light using the power supplied thereto.

As illustrated in FIGS. 1 and 2, the floodlight 100A includes: a main-body member 10 that includes a light emitter unit 12 including light sources 17; a handle 13 that is coupled to the main-body member 10; an arm 20 that is coupled to a coupling mechanism 30 provided on a side face of the main-body member 10 and is pivotable about a rotational axis AX; an operation device HD that is disposed in the coupling mechanism 30 and is operated to adjust the light emission state of the light emitter unit 12; and a control device 60. The light emission state of the light emitter unit 12 is a concept including the light emission state of the light source 17.

In the explanation hereunder, positional relations between the parts will be explained using terms such as "front", "rear", "up", "down", "left", and "right". The light emitter unit 12 is disposed downward of a center of the main-body member 10. The handle 13 is disposed upward of the center of the main-body member 10. A downward direction is the direction opposite to an upward direction, and a rearward direction is the direction opposite to the forward direction. Lateral directions are directions that perpendicularly intersect with the forward and the upward directions. One of the lateral directions is the leftward direction, and the other lateral direction is the rightward direction.

Main-Body Member

The main-body member 10 includes a housing 11, the light emitter unit 12 that is supported by the housing 11, and a heat-radiating member 19 that supports the light emitter unit 12. The heat-radiating member 19 is supported by the housing 11. The housing 11 includes a front cover 14, a rear cover 15, and a battery cover 16. The front cover 14 is disposed forward of the rear cover 15. The front cover 14 is disposed around the light emitter unit 12. The light emitter unit 12 and the heat-radiating member 19 are housed inside of the front cover 14. The front cover 14 is made of elastomer, for example. The front cover 14 includes a lens 14L. The lens 14L is disposed forward of the light emitter unit 12. The lens 14L is made of a material capable of transmitting light. The front cover 14 has a plurality of faces that are disposed around the light emitter unit 12 and the heat-radiating member 19. The faces of the front cover 14 include a top face 14a, a bottom face 14b, a right face 14c, and a left face 14d of the front cover 14. At least two of the top face 14a, the bottom face 14b, the right face 14c, and the left face 14d of the front cover 14 are provided with openings 14K, respectively. In this embodiment, each of the top face 14a, the bottom face 14b, the right face 14c, and the left face 14d of the front cover 14 is provided with the opening 14K. The openings 14K serve as vents that connect the internal space of the front cover 14 to the external space. At least a part of the heat-radiating member 19 is exposed via the openings 14K. The heat in the light emitter unit 12 and the heat-radiating member 19 is radiated outside the housing 11, via the openings 14K. Even when the light emitter unit 12 is a high power unit, the heat generated in the light emitter unit 12 is radiated outside effectively via the openings 14K. Furthermore, even if a foreign substance gets inside of the front cover 14 via the opening 14K provided to any one of the top face 14a, the bottom face 14b, the right face 14c, and the left face 14d, the foreign substance is discharged outside the front cover 14 via the openings 14K.

provided to another one of the faces. The foreign substance is a concept including one or both of a solid such as a dust, and a liquid such as water.

The rear cover 15 is disposed rearward of the front cover 14. The rear cover 15 has a stepped portion 15a protruding upward. The top face of the stepped portion 15a is disposed at almost the same level as the top face of the front cover 14 in the up-and-down direction. The rear cover 15 has a first wall 15S. The first wall 15S is provided on the front part of the rear cover 15. The rear cover 15 is fastened to the front cover 14 via the first wall 15S.

The battery cover 16 is disposed rearward of the rear cover 15. The battery cover 16 is coupled to a lower part of the rear cover 15 via a hinge mechanism. The battery cover 16 is pivotably supported by the rear cover 15. The battery cover 16 may be detachably disposed to the rear cover 15. The battery cover 16 has a latch 16a protruding toward the rear cover 15. The latch 16a is disposed on the top face of the stepped portion 15a.

The light emitter unit 12 includes the light sources 17, and a control board 18 that supports the light sources 17. Light-emitting diodes (LEDs), for example, are used as the light sources 17. The light sources 17 are arranged in the up-and-down direction and the left-to-right direction, on the front face of the control board 18. The light sources 17 may emit light having the same color, or emit light having different colors. The control board 18 includes a driving circuit for driving the light sources 17, and a wiring that is connected to the driving circuit. The control board 18 controls the light emission state of the light emitter unit 12, based on a control signal from the control device 60. The heat-radiating member 19 is in contact with the control board 18. The control board 18 is fastened to the heat-radiating member 19. As described earlier, the heat-radiating member 19 is supported by the housing 11. The control board 18 supporting the light sources 17 is supported by the housing 11 via the heat-radiating member 19.

The heat-radiating member 19 is a heat sink for radiating the heat generated by the light sources 17. The heat-radiating member 19 is made of a material having a higher thermal conductivity than that of the material of which the control board 18 is made. For example, the heat-radiating member 19 is made of a metallic material such as aluminum. The heat-radiating member 19 may be made of a material containing carbon, for example.

Handle

The handle 13 is attached to the main-body member 10. The handle 13 has a pair of base portions 13a that are coupled to the rear cover 15 via a shaft portion 13b, and a holding portion 13c that connects the pair of base portions 13a. The base portions 13a are attached to the right and the left side faces of the stepped portion 15a, respectively, via the shaft portion 13b. The pivoting axis of the shaft portion 13b is in parallel with the rotational axis AX. The rotational axis AX extends along the left-to-right direction. The base portions 13a are pivotable about the shaft portion 13b. The base portions 13a extend linearly from the stepped portion 15a. The holding portion 13c is held by a worker. The worker can carry the floodlight 100A by holding the holding portion 13c.

The handle 13 can be moved between a housed position P1 and a standing position P2 (see FIG. 6, for example), by pivoting the base portions 13a about the shaft portion 13b.

When the handle 13 is positioned at the housed position P1, the handle 13 is laid along the left side, the right side, and the rear side of the stepped portion 15a. The shape and the size of the handle 13 are determined in such a manner

that the base portions **13a** and the holding portion **13c** do not jut out from the rear cover **15**, and that the top face of the handle **13** does not jut out upward from the front cover **14**, when the handle **13** is disposed at the housed position **P1**.

When the handle **13** is positioned at the housed position **P1**, the handle **13** is laid on top of the battery cover **16**. By positioning the handle **13** on top of the battery cover **16**, a rearward movement of the battery cover **16** (open direction) is restricted. By positioning the handle **13** at the housed position **P1**, the battery cover **16** is suppressed from unexpectedly opening.

When the handle **13** is positioned at the standing position **P2**, a worker can hold the handle **13** smoothly.

Arm

The arm **20** is coupled to the coupling mechanism **30** provided on the side faces of the main-body member **10**, and is pivotable about the rotational axis **AX**. The arm **20** has a first base portion **21**, a second base portion **22**, and an annular portion **23**. The first base portion **21**, the second base portion **22**, and the annular portion **23** are integrated. The coupling mechanism **30** includes a first coupling mechanism **31** provided on a first side face **15R** of the main-body member **10**, and a second coupling mechanism **32** provided on the second side face **15L** of the main-body member **10**. The first side face **15R** is the right side face of the rear cover **15**, and the second side face **15L** is the left side face of the rear cover **15**.

The first base portion **21** is coupled to the first side face **15R** of the rear cover **15** via the first coupling mechanism **31**. The first base portion **21** is linear, and extends forward and downward from the first coupling mechanism **31** along the first side face **15R**. The first base portion **21** is connected to the annular portion **23** via a curved portion **24**. The second base portion **22** is coupled to the second side face **15L** of the rear cover **15** via the second coupling mechanism **32**. The second base portion **22** is linear, and extends forward and downward from the second coupling mechanism **32** along the second side face **15L**. The first base portion **21** has the same size as the second base portion **22**. The second base portion **22** is connected to the annular portion **23** via a curved portion **25**.

The annular portion **23** has a first section **23a** disposed along the first side face **15R**, a second section **23b** disposed along the second side face **15L**, and a third section **23c** disposed in parallel with the rotational axis **AX**. The first section **23a** is connected to the curved portion **24**. The second section **23b** is connected to the curved portion **25**. The right end of the third section **23c** is connected to the first section **23a** via a curved portion **26**. The left end of the third section **23c** is connected to the second section **23b** via a curved portion **27**.

The first coupling mechanism **31** is provided on the first side face **15R**. The second coupling mechanism **32** is provided on the second side face **15L**. The second coupling mechanism **32** includes a fastening mechanism **35** for fastening the arm **20** to the main-body member **10**. The fastening mechanism **35** includes a cam **32c** that restricts pivoting movements of the arm **20**.

First Coupling Mechanism and Operation Device

FIG. 3 is a cross-sectional view of the operation device **HD** according to the embodiment, and corresponds to the cross-sectional view taken along the arrow line A-A in FIG. 2. The operation device **HD** is disposed in the coupling mechanism **30**, and is operated to adjust the light emission state of the light emitter unit **12** (the light sources **17**). The operation device **HD** includes a switch mechanism **40** and a dial mechanism **50**.

As illustrated in FIG. 3, the operation device **HD** is disposed in the first coupling mechanism **31**. The operation device **HD** is provided independently from the first base portion **21**. The first coupling mechanism **31** includes a flange portion **31a** and a cylindrical portion **31b**. The flange portion **31a** is fastened to the first side face **15R**. The cylindrical portion **31b** protrudes rightward from the flange portion **31a**. The central axis of the cylindrical portion **31b** is coincident with the rotational axis **AX**. The first base portion **21** is supported pivotably about the rotational axis **AX** by the cylindrical portion **31b**.

At least a part of the switch mechanism **40** is laid along the rotational axis **AX** of the first coupling mechanism **31**. At least a part of the dial mechanism **50** is disposed around the switch mechanism **40**. The switch mechanism **40** includes a switch **41**, a moving member **42**, and a displacement sensor **43**. The dial mechanism **50** includes a dial **51**, a rotating member **52**, and a rotation sensor **53**.

At least part of the switch **41** is laid along the rotational axis **AX**, and is capable of being displaced in a direction parallel with the rotational axis **AX**. The right end of the switch **41** protrudes rightward from the dial **51**. The dial **51** is disposed around the switch **41**. The switch **41** is capable of being displaced in the left-to-right directions on the inner side of the dial **51**. A worker can cause the switch **41** to be displaced by pushing the right end of the switch **41**. The switch **41** is independent from the first base portion **21** and the first coupling mechanism **31**. Therefore, the first base portion **21** and the first coupling mechanism **31** do not move even when the switch **41** is operated.

An elastic member such as a spring may be connected to the switch **41** to keep the right end of the switch **41** jutting out of the dial **51**.

The moving member **42** is coupled to the switch **41**. The moving member **42** has a columnar shape. The central axis of the moving member **42** is coincident with the rotational axis **AX**. The moving member **42** is inserted into an insertion hole **15c** that is provided to the rear cover **15**. As the switch **41** is displaced in the left-to-right directions, the moving member **42** is displaced, together with the switch **41**, in the left-to-right directions.

The displacement sensor **43** detects the amount by which the switch **41** is displaced. The displacement sensor **43** is disposed to be in contact with the left end of the moving member **42**. The displacement sensor **43** outputs an electric signal based on the amount by which moving member **42** is displaced. The displacement sensor **43** may be a contact sensor such as a piezoelectric sensor, or a non-contact sensor such as an optical sensor or a magnetic sensor.

The dial **51** is disposed around the switch **41**, and is rotatable about the rotational axis **AX**. The dial **51** has a cylindrical shape. The central axis of the dial **51** is coincident with the rotational axis **AX**. The dial **51** is a multi-turn dial that can be freely rotated, without any rotatable range. The dial **51** may be a dial with a specified rotatable range. A worker can operate the dial **51**. A worker can rotate the dial **51** by holding the dial **51** with his/her fingers. The dial **51** is independent from the first base portion **21** and the first coupling mechanism **31**. Therefore, the first base portion **21** and the first coupling mechanism **31** are not rotated even when the dial **51** is operated.

The rotating member **52** is coupled to the dial **51**. The rotating member **52** has a cylindrical shape. The central axis of the rotating member **52** is coincident with the rotational axis **AX**. The rotating member **52** is inserted into the insertion hole **15c** provided to the rear cover **15**. The inner diameter of the rotating member **52** is larger than the outer

diameter of the moving member 42. The moving member 42 is disposed inside the rotating member 52. The rotating member 52 is supported on the inner circumferential surface of the insertion hole 15c via a bearing 15d.

The rotation sensor 53 detects the amount by which the dial 51 is rotated. The rotation sensor 53 outputs an electric signal based on the amount by which the rotating member 52 is rotated. The rotation sensor 53 may be a non-contact sensor such as an optical sensor or a magnetic sensor.

A wall 15e having a double-ring shape is provided to the inner circumferential surface of the insertion hole 15c. The wall 15e holds a seal member 15f such as an O ring. The seal member 15f suppresses the entry of a foreign substance into the insertion hole 15c, in which the displacement sensor 43 and the rotation sensor 53 are disposed, from the external.

Second Coupling Mechanism

FIG. 4 is a perspective view of the second coupling mechanism 32 according to the embodiment. As illustrated in FIG. 4, the second base portion 22 has a columnar portion 22a, a rod-like portion 22b, and a cam 22c. The columnar portion 22a is coupled to the second coupling mechanism 32. The rod-like portion 22b is coupled to the columnar portion 22a, and is coupled to the annular portion 23. The cam 22c restricts pivoting movements of the arm 20. The cam 22c is provided on a right tip end surface 22d of the columnar portion 22a. FIG. 4 also illustrates the columnar portion 22a seen from the side of the tip end surface 22d. The cam 22c has a plurality of protrusions that are arranged along the circumferential direction of the columnar portion 22a.

The second coupling mechanism 32 includes the fastening mechanism 35 for fastening the arm 20 to the main-body member 10. The fastening mechanism 35 includes a flange portion 32a, a columnar portion 32b, the cam 32c, a screw portion 32d, and a fastening member 32e. The flange portion 32a is fastened to the second side face 15L. The columnar portion 32b protrudes leftward from the flange portion 32a. The central axis of the columnar portion 32b is coincident with the rotational axis AX.

The cam 32c restricts pivoting movements of the arm 20. The cam 32c is provided to a tip end surface 32f of the columnar portion 32b. The cam 32c has a plurality of protrusions that are arranged along the circumferential direction of the columnar portion 32b.

The screw portion 32d protrudes leftward from the tip end surface 32f of the columnar portion 32b. The left end of the screw portion 32d has a male thread. The screw portion 32d is inserted into a through hole 22e provided to the columnar portion 22a of the second base portion 22.

The fastening member 32e has a screw hole 32g having a female thread. The female thread of the screw hole 32g is enmeshed with the male thread of the screw portion 32d. The fastening member 32e is enmeshed with the screw portion 32d from the left side of the columnar portion 22a. The columnar portion 22a and the columnar portion 32b are fastened to each other by inserting the left end of the screw portion 32d into the screw hole 32g provided to the fastening member 32e, and rotating the fastening member 32e in one of the rotating directions about the rotational axis AX. The fastening of the columnar portion 22a and the columnar portion 32b is loosened by rotating the fastening member 32e in the other rotating direction about the rotational axis AX.

With the columnar portion 22a and the columnar portion 32b fastened to each other, the cam 22c of the second base portion 22 and the cam 32c of the second coupling mecha-

nism 32 are enmeshed with each other. As a result, rotations of the columnar portion 22a about the rotational axis AX are restricted.

With fastening between the columnar portion 22a and the columnar portion 32b loosened, the mesh between the cam 22c of the second base portion 22 and the cam 32c of the second coupling mechanism 32 is released. As a result, the columnar portion 22a can be rotated about the rotational axis AX. Furthermore, with the mesh between the cam 22c and the cam 32c released, the position of the arm 20 in the rotating direction about the rotational axis AX can be adjusted.

10 The annular portion 23 couples the first base portion 21 and the second base portion 22. The annular portion 23 is curved forward from the first base portion 21 and the second base portion 22. The annular portion 23 includes a cable-winding portion 23d around which a cable for connecting the main-body member 10 and an AC power source is wound, and a connecting portion 23e that is connected to a tripod or a vise.

Heat-Radiating Member

FIG. 5 is a perspective view of the heat-radiating member 19 according to the embodiment. FIG. 5 illustrates the heat-radiating member 19 housed inside the front cover 14, from a viewpoint on the rear side. As illustrated in FIG. 5, the heat-radiating member 19 includes a support panel 19a, fins 19b and fins 19c, a fastening member inserting portion 19d, and a pass-through portion 19e. The support panel 19a supports the control board 18. The control board 18 is in contact with the support panel 19a. The fins 19b and the fins 19c are supported by the rear face of the support panel 19a, and protrude rearward from the support panel 19a. The fins 19b each have a plate-like shape extending in the up-and-down direction, and are provided with a space therebetween in the left-to-right direction. The fins 19c each have a plate-like shape extending in the left-to-right direction, and are provided with a space therebetween in the up-and-down direction. A fastening member for fastening the heat-radiating member 19 is inserted into the fastening member inserting portion 19d. Wirings connected to the control board 18 are placed inside of the pass-through portion 19e.

Battery Mounting Unit

FIGS. 6 and 7 are perspective views of the floodlight 100A according to this embodiment, seen from the rear side, with the battery cover 16 pivoted rearward (open direction). The main-body member 10 includes a battery mounting unit 70 where an electric-tool battery 80 is mounted. The electric-tool battery 80 is a rechargeable battery. The battery mounting unit 70 is covered with the battery cover 16. When the electric-tool battery 80 is to be mounted on the battery mounting unit 70, or when the electric-tool battery 80 is to be removed from the battery mounting unit 70, the battery cover 16 is pivoted rearward. FIG. 6 illustrates the battery mounting unit 70 with the electric-tool batteries 80 removed. FIG. 7 illustrates the battery mounting unit 70 with the electric-tool batteries 80 mounted.

When the battery cover 16 is to be pivoted rearward, the handle 13 is lifted so that the handle 13 comes to the standing position P2. As a result, the battery cover 16 is in a pivotable state. After the handle 13 is positioned at the standing position P2, by removing the latch 16a, the battery cover 16 is pivoted in a direction in which an upper part of the battery cover 16 moves rearward. Once the battery cover 16 is pivoted rearward, the battery mounting unit 70 becomes exposed, as illustrated in FIG. 6. When the battery cover 16 is pivoted forward (close direction), the latch 16a

is moved to the position above the stepped portion **15a**, and the battery mounting unit **70** is covered with the battery cover **16**.

The battery mounting unit **70** is disposed rearward of the light emitter unit **12**, and at least two electric-tool batteries **80** can be mounted thereon. The rear cover **15** has a second wall **15T**. The second wall **15T** is provided on the rear part of the rear cover **15**. The battery mounting unit **70** is disposed on the second wall **15T**. Two battery mounting units **70** are provided on the second wall **15T** in the left-to-right direction. The number of the battery mounting units **70** may be one, or any number equal to or more than three. The battery mounting unit **70** may be provided in plurality in the up-and-down directions.

The electric-tool battery **80** is mounted on the battery mounting unit **70**. The battery mounting unit **70** has a guide portion **71** for guiding the electric-tool battery **80**. The electric-tool battery **80** is mounted on the battery mounting unit **70** by sliding the electric-tool battery **80** downward with respect to the battery mounting unit **70**, with the guide of the guide portion **71**. By mounting the electric-tool battery **80** on the battery mounting unit **70**, the main-body member **10** can be energized by the electric-tool battery **80**. The light emitter unit **12**, the switch mechanism **40**, the dial mechanism **50**, and the control device **60** are driven by the power supplied from the electric-tool battery **80**. A remaining charge signal indicating the remaining charge in the electric-tool battery **80** is output to the control device **60**.

Power Supply Cable

FIG. 8 is a perspective view of the floodlight **100A** according to this embodiment seen from the rear side, with a power supply cable **15r** connected to the floodlight **100A**. As illustrated in FIG. 8, a connector connecting portion **15p** is provided on the rear face **15B** of the rear cover **15**. A connector **15t** of the power supply cable **15r** is connected to the connector connecting portion **15p**. The connector connecting portion **15p** is covered with a connecting portion cover **15g**. The connecting portion cover **15g** is coupled to the rear face **15B** via a hinge mechanism. FIG. 8 illustrates the opened connecting portion cover **15g**.

Internal Space

FIG. 9 is a cross-sectional view of the floodlight **100A** according to this embodiment, and corresponds to a cross-sectional view taken along the arrow line B-B in FIG. 2. As illustrated in FIG. 9, the housing **11** has an internal space in which the light emitter unit **12**, the heat-radiating member **19**, and the electric-tool battery **80** are housed. The internal space of the housing **11** is partitioned into a first space **K1** in which the heat-radiating member **19** is housed, and a second space **K2** in which the electric-tool batteries **80** are housed. The first space **K1** is defined by the front cover **14** and the first wall **15S** of the rear cover **15**. The front cover **14** is fastened to the first wall **15S**, using a screw member **15u**. The second space **K2** is defined by the second wall **15T** of the rear cover **15** and the battery cover **16**. The battery cover **16** suppresses the entry of a foreign substance into the second space **K2**.

Control Device

FIG. 10 is a functional block diagram illustrating the control device **60** according to the embodiment. The control device **60** includes a processor that includes a central processing unit (CPU), and a storage device that includes a random access memory (RAM) or a read-only memory (ROM). The control device **60** is placed in the internal space of the rear cover **15**, for example.

The control device **60** includes an input unit **61**, a light emission state control unit **62**, and a storage unit **63**.

The input unit **61** acquires input signals. The input signals acquired by the input unit **61** include a detection signal from the displacement sensor **43**, a detection signal from the rotation sensor **53**, and a remaining charge signal from the electric-tool battery **80**.

The light emission state control unit **62** outputs a control signal for controlling the light emission state of the light emitter unit **12** (the light sources **17**), based on an amount by which the operation device **HD** is operated. The amount by which the operation device **HD** is operated includes the amount by which the switch **41** is displaced and the amount by which the dial **51** is rotated. The light emission state control unit **62** controls the light emission state of the light emitter unit **12** based on the input signal input to the input unit **61**. The light emission state control unit **62** includes a first light emission state control unit **64** and a second light emission state control unit **65**.

The first light emission state control unit **64** outputs a control signal for controlling the light emission state of the light emitter unit **12** (the light sources **17**) based on the amount by which the displacement sensor **43** is operated. The light emission state control of the light emitter unit **12**, which is performed by the first light emission state control unit **64**, includes at least one of control for switching the light emitter unit **12** between an on state, a blinking state, and an off state, and control for switching the color of the light emitted from the light emitter unit **12**. The first light emission state control unit **64** performs, as the light emission state control, at least one of the control for switching the light emitter unit **12** between the on state, the blinking state, and the off state, and control for switching the color of the light emitted from the light emitter unit **12**.

When a worker operates the switch **41** of the switch mechanism **40**, the displacement sensor **43** detects the amount by which the switch **41** is displaced. The displacement sensor **43** then outputs the detection signal to the control device **60**. The first light emission state control unit **64** then controls the light emission state of the light emitter unit **12** based on the detection signal input from the displacement sensor **43** to the input unit **61**.

The first light emission state control unit **64** be may configured to switch the light emission state between the on state, the blinking state, and the off state, based on the time for which the switch **41** is operated, or based on the time from when the switch **41** is operated for the first time to when the switch **41** is operated next time. For example, the first light emission state control unit **64** may be configured to control the light emission state so that the light emission state is changed between when a worker operates the switch **41** for time equal to or longer than a predetermined time (when pressed long), and when the worker operates the switch **41** for time equal to or less than the predetermined time.

Furthermore, if the switch **41** is operated for time equal to or longer than the predetermined time while the light emitter unit **12** is on, the first light emission state control unit **64** may change the light emission state to the off state, and if the switch **41** is operated for time equal to or less than the predetermined time, change the light emission state to the blinking state, or maintain the on state. If the switch **41** is operated for time equal to or longer than the predetermined time while the light emitter unit **12** is off, the first light emission state control unit **64** may change the light emission state to the on state, and if the switch **41** is operated for time equal to or less than the predetermined time, change the light emission state to the blinking state, or maintain the off state.

11

Furthermore, if the switch 41 is operated for time equal to or longer than the predetermined time while the light emitter unit 12 is emitting light in a first color, the first light emission state control unit 64 may change the light emission state to a state of emitting light in a second color, and, if the switch 41 is operated for time equal to or less than the predetermined time, change the light emission state to a state of emitting light in a third color, or maintain the state of emitting light in the first color.

Furthermore, the first light emission state control unit 64 may be configured to control to change the light emission state to a different light emission state when the switch 41 is operated for the second time within a predetermined time since when the switch 41 is operated for the first time, for example.

Furthermore, the first light emission state control unit 64 may be configured to control the light emission state of the light emitter unit 12 based on the detection signal from the rotation sensor 53. For example, with a configuration in which the dial 51 has a limited rotatable range, the first light emission state control unit 64 may change the light emission state of the light emitter unit 12 to the off state when the rotational position of the dial 51 reaches the lower boundary or the upper boundary of the rotatable range.

Furthermore, the first light emission state control unit 64 may be configured to control the light emission state of the light emitter unit 12 based on the remaining charge signal from the electric-tool battery 80. For example, when the remaining charge signal from the electric-tool battery 80 drops to a level lower than a remaining charge threshold while the light emitter unit 12 is on, the first light emission state control unit 64 may change the light emission state to the blinking state of the light emitter unit 12, or to change the color of the light emitted from the light emitter unit 12.

The second light emission state control unit 65 outputs a control signal for controlling the light emission state of the light emitter unit 12 (the light sources 17) based on the detection signal from the rotation sensor 53. The light emission state control performed by the second light emission state control unit 65 includes control of illuminance on a predetermined illuminance reference surface F (see FIG. 2) irradiated with the light emitted from the light emitter unit 12. The illuminance reference surface F is a virtual plane defined at a position that is away from the light emitter unit 12 by a predetermined distance in a forward direction. The illuminance takes a higher value when the quantity of the light emitted from the light emitter unit 12 is greater, and takes a lower value when the quantity of light is smaller. The quantity of the light emitted from the light emitter unit 12 is the sum of the quantities of light emitted from the respective light sources 17. The quantity of the light emitted from a light source 17 takes a greater value when the current supplied to the light source 17 is higher, and takes a smaller value when the current is lower. Therefore, the illuminance on the illuminance reference surface F changes depending on the current supplied to the light sources 17. The light emission state control performed by the second light emission state control unit 65 includes control of the current supplied to the light sources 17. The storage unit 63 stores therein correlation data indicating a relation between a current supplied to the light sources 17, and illuminance corresponding to the current, on the illuminance reference surface F. The correlation data can be obtained in advance, by carrying out experiments or simulations. When the illuminance on the illuminance reference surface F is to be changed, the second light emission state control unit 65 sets

12

a target current corresponding to the illuminance after the change, and controls the current supplied to the light sources 17 based on the set target.

The second light emission state control unit 65 may be configured to control the illuminance on the illuminance reference surface F, that is, the current supplied to the light sources 17, based on a detection signal from the rotation sensor 53, for example. When a worker rotates the dial 51 on the dial mechanism 50, the rotation sensor 53 detects the amount by which the dial 51 is rotated. The rotation sensor 53 then outputs the detection signal to the control device 60. The second light emission state control unit 65 then controls the current supplied to the light sources 17 based on the detection signal that is input from the rotation sensor 53 to the input unit 61.

The second light emission state control unit 65 may be configured to control the current supplied to the light sources 17 based on a remaining charge in the electric-tool battery 80 that is mounted on the battery mounting unit 70, for example. The electric-tool battery 80 outputs a remaining charge signal indicating the remaining charge. The second light emission state control unit 65 then detects the remaining charge in the electric-tool battery 80, based on the remaining charge signal output from the electric-tool battery 80. If the remaining charge in the electric-tool battery 80 drops to a level lower than a remaining charge threshold, the second light emission state control unit 65 reduces the level of current supplied to the light sources 17.

The storage unit 63 stores therein the illuminance controlled by the control of the second light emission state control unit 65, that is, a target current. The storage unit 63 includes an illuminance data storage unit 66 storing therein a target of a current corresponding to an illuminance on the illuminance reference surface F. The second light emission state control unit 65 stores the set target current in the storage unit 63, at a constant cycle. When the light emitter unit 12 is to be turned off once, and then to be turned on again, for example, the second light emission state control unit 65 controls the current supplied to the light sources 17 based on the target current stored in the storage unit 63 at the last cycle while the light emitter unit 12 is off.

Use Mode

Explained now is how the floodlight 100A according to this embodiment is used. The floodlight 100A is used on a worksite where workers work using some electric tools, for example. The floodlight 100A may be placed on the ground or on an installation table. When the floodlight 100A is a stationary floodlight that is to be placed directly on the ground or an installation table, the arm 20 is disposed downward of the main-body member 10. The direction in which the light is emitted from the light emitter unit 12 is adjusted by adjusting the positional relation of the main-body member 10 with respect to the arm 20, by rotating the main-body member 10 about the rotational axis AX.

FIG. 11 is a schematic illustrating how the floodlight 100A according to this embodiment is used. As illustrated in FIG. 11, the floodlight 100A may be supported on a special tripod stand 90. The floodlight 100A is supported on the tripod stand 90 by connecting the connecting portion 23e provided to the annular portion 23 of the arm 20 to the tripod stand 90.

The floodlight 100A may be supported on a tripod stand designed for use for another purpose, such as a tripod stand for attaching a laser marker, or a tripod stand for attaching a camera. Furthermore, the tripod stand 90 can support a

13

plurality of floodlights 100A, by attaching an attachment capable of coupling a plurality of floodlights 100A, to the tripod stand 90.

When the switch 41 of the switch mechanism 40 is operated to switch the light emitter unit 12 between the on state, the blinking state, and the off state, the displacement sensor 43 outputs a detection signal to the control device 60, based on the amount by which the switch 41 is displaced. The control device 60 then switches the light emitter unit 12 between the on state, the blinking state, and the off state based on the detection signal from the displacement sensor 43.

When the dial 51 on the dial mechanism 50 is operated to control the illuminance of the light emitted from the light emitter unit 12, the rotation sensor 53 outputs a detection signal to the control device 60 based on the amount by which the dial 51 is rotated. The control device 60 then changes the level of current supplied to the light sources 17, based on the detection signal from the rotation sensor 53.

In this manner, the worker can operate the operation device HD disposed on the first side face 15R that is one of the first side face 15R and the second side face 15L that are the side faces of the main-body member 10. Therefore, even a worker who is holding an electric tool in one hand can operate the operation device HD with the other hand, for example. Furthermore, because the switch 41 and the dial 51 are disposed on the side face of the main-body member 10, a worker can operate the switch 41 and the dial 51 easily even when the floodlight 100A is placed at a high place.

Furthermore, for example, in an operation of pivoting the arm 20 with respect to the main-body member 10, the arm 20 can be pivoted easily, because fastening of the cam 22c and the cam 32c is loosened by rotating the fastening member 32e in the one direction for loosening the fastening. Furthermore, when the columnar portion 22a is aligned with the columnar portion 32b by pivoting the arm 20, and the fastening member 32e is then rotated in the other direction, the columnar portion 22a is fastened. When a worker is to pivot the arm 20 in the manner described above, the worker can operate the fastening mechanism 35 disposed on the second side face 15L that is the other side face of the first side face 15R and the second side face 15L of the main-body member 10. Therefore, even a worker who is holding an electric tool in one hand can operate the fastening mechanism 35 easily using the other hand.

Advantageous Effects

As explained above, the floodlight 100A according to this embodiment includes the main-body member 10 that includes the light emitter unit 12, the arm 20 that is coupled to the coupling mechanism 30 provided on the side faces of the main-body member 10, and that is pivotable about the rotational axis AX, and the operation device HD that is disposed in the coupling mechanism 30, and that is operated to adjust the light emission state of the light emitter unit 12.

According to this embodiment, because the operation device HD that is operated to adjust the light emission state of the light emitter unit 12 is laid along the rotational axis AX of the coupling mechanism 30, the operation device HD does not interfere with the arm 20. Furthermore, because the operation device HD is disposed on the lateral side of the main-body member 10, the operation for adjusting the light emission state can be performed smoothly, even when the main-body member 10 is placed at a high place.

In this embodiment, the coupling mechanism 30 includes the first coupling mechanism 31 provided on the first side

14

face 15R of the main-body member 10, and the second coupling mechanism 32 provided on the second side face 15L of the main-body member 10. The operation device HD is disposed in the first coupling mechanism 31, and the second coupling mechanism 32 includes the fastening mechanism 35 for fastening the arm 20 to the main-body member 10. With this configuration, the operation device HD is suppressed from being operated unintentionally while the fastening member 32e of the fastening mechanism 35 is being operated. The fastening member 32e is also suppressed from being operated unintentionally while the operation device HD is being operated.

In this embodiment, the fastening mechanism 35 includes the cam 32c that restricts pivoting movements of the arm 20. Because the cam 32c restricts the pivoting movements of the arm 20, the pivoting movements of the arm 20 can be restricted even without providing a fastening mechanism to the first coupling mechanism 31.

In this embodiment, the operation device HD includes the switch 41 at least a part of which is laid along the rotational axis AX, and that is displaceable in a direction parallel with the rotational axis AX, and the dial 51 that is disposed around the switch 41, and that is rotatable about the rotational axis AX. Because the switch 41 and the dial 51 that are operated differently are provided as the operation device HD, a worker can operate the operation device HD easily.

In this embodiment, the light emission state control unit 62 for controlling the light emission based on the amount by which the operation device HD is operated is provided. The amount by which the operation device HD is operated includes the amount by which the switch 41 is displaced and the amount by which the dial 51 is rotated. In this manner, the operations of the switch 41 and the dial 51 are reflected appropriately to the light emission state.

In this embodiment, the displacement sensor 43 for detecting the amount by which the switch 41 is displaced is provided. The light emission state control unit 62 includes the first light emission state control unit 64 that controls the light emission state based on the detection signal from the displacement sensor 43. With this configuration, an operation of the switch 41 is reflected appropriately to the light emission state.

In this embodiment, the light emission state control performed by the first light emission state control unit 64 includes at least one of the control for causing the light emitter unit 12 (the light sources 17) to switch between the on state, the blinking state, and the off state, and control for switching the color of the light emitted from the light emitter unit 12. With this control, the state of the light emitted from the light emitter unit 12 can be changed variously.

In this embodiment, the rotation sensor 53 for detecting the amount by which the dial 51 is rotated is provided. The light emission state control unit 62 includes the second light emission state control unit 65 that controls the light emission state based on the detection signal from the rotation sensor 53. With this configuration, an operation of the dial 51 is reflected appropriately as a change in the illuminance.

In this embodiment, the light emission state control performed by the second light emission state control unit 65 includes the control of illuminance on the predetermined illuminance reference surface F irradiated with the light emitted from the light emitter unit 12 (the light sources 17). With this configuration, the light emitter unit 12 can emit light at various light quantities.

In this embodiment, the storage unit 63 for storing therein the illuminance achieved by the control of the second light emission state control unit 65 is provided. When the light

15

emitter unit **12** (the light sources **17**) having been off is to be turned on, the second light emission state control unit **65** controls the light emitter unit **12** (the light sources **17**) to emit light at the illuminance that is stored in the storage unit **63** during the time in which the light emitter unit **12** (the light sources **17**) is off. When the light emitter unit **12** is to be turned on again, the light is emitted at the illuminance at which light has been emitted by the light emitter unit **12** immediately previously. Therefore, it is not necessary to go through cumbersome re-adjustment of the illuminance of the light emitter unit **12**.

In this embodiment, the battery mounting unit **70** on which the electric-tool battery **80** is mounted is provided to the main-body member **10**. The light emission state control unit **62** controls the light emission state based on the remaining charge of the battery mounted on the battery mounting unit **70**. With this configuration, a notification of the remaining charge of the electric-tool battery **80** is sent to the external, effectively.

In this embodiment, the battery mounted on the battery mounting unit **70** is the electric-tool battery **80** capable of being mounted on electric tools. With this configuration, on a worksite in which electric tools are used, the electric-tool battery **80** used in the electric tools can be also used in the floodlight **100A**.

In this embodiment, at least two electric-tool batteries **80** can be mounted on the battery mounting unit **70**. With this configuration, enough power to allow the light emitter unit **12** to emit light can be ensured.

In this embodiment, the main-body member **10** has the heat-radiating member **19** to which the light emitter unit **12** is fastened, and the front cover **14** that is disposed around the light emitter unit **12**, and that has the faces (the top face **14a**, the bottom face **14b**, the right face **14c**, the left face **14d**) surrounding the light emitter unit **12** and the heat-radiating member **19**; and at least two faces of the front cover **14** are provided with the openings **14K**. With this configuration, even if a foreign substance gets inside of the front cover **14** via the opening **14K** provided to one of the faces of the front cover **14**, the foreign substance is discharged from the opening **14K** provided to another side face.

In this embodiment, the main-body member **10** has the first wall **15S** that forms, together with the front cover **14**, the first space **K1** for housing the heat-radiating member **19**, the second wall **15T** on which the battery mounting unit **70** is disposed, and the battery cover **16** that forms, together with the second wall **15T**, the second space **K2** in which the electric-tool battery **80** is housed. The battery cover **16** can restrict entry of a foreign substance into the second space **K2**.

Second Embodiment

A second embodiment will now be explained. In the explanation below, the elements that are the same as those according to the embodiment described above are assigned with the same reference signs, and explanations thereof will be simplified or omitted.

FIG. **12** is a perspective view of one example of a floodlight **100B** according to this embodiment. The floodlight **100B** includes the main-body member **10**, the arm **20**, the coupling mechanism **30**, and the operation device **HD**, in the same manner as in the embodiment described above. The floodlight **100B** according to this embodiment is different from the embodiment described above in having hooks **131**, instead of the handle **13** explained in the embodiment. The

16

hooks **131** are coupled to the main-body member **10**, and are hooked onto a rod-like member **91**.

FIG. **13** is a schematic illustrating how the floodlight **100B** according to this embodiment is used. As illustrated in FIG. **13**, the arm **20** of the floodlight **100B** is pivotable about a pivoting axis that connects the coupling mechanism **30**. With the hooks **131** hooked onto the rod-like member **91**, the arm **20** is pivoted about the rotational axis **AX**, and is coupled to the tips of the hooks **131**. The arm **20** is coupled to the tips of the hooks **131** in such a manner that the rod-like member **91** is surrounded thereby. According to this embodiment, the hooks **131** is suppressed from unhooking.

Third Embodiment

A third embodiment will now be explained. In the explanation below, the elements that are the same as those according to the embodiment described above are assigned with the same reference signs, and explanations thereof will be simplified or omitted.

FIG. **14** is a perspective view of one example of a floodlight **1000** according to this embodiment. The floodlight **100C** includes the main-body member **10**, the arm **20**, the coupling mechanism **30**, and the operation device **HD**, in the same manner as in the embodiment described above. The floodlight **100C** according to this embodiment is different from the embodiment described above in having hooks **132**, instead of the handle **13** explained in the embodiment. The hooks **132** can be hanged on the rod-like member **91**. The hooks **132** are disposed on the respective lateral sides of the main-body member **10**. The hooks **132** are supported by bearings **133** that are pivotable about pivoting axes that are in parallel with a front-and-rear direction. The hook **132** disposed on the right side of the main-body member **10** is bent rearward. The hook **132** disposed on the left side of the main-body member **10** is bents forward.

FIG. **15** is a schematic illustrating how the floodlight **100C** according to this embodiment is used. As illustrated in FIG. **15**, in the floodlight **100B**, after the hooks **132** on the right and the left sides are removed from the rod-like member **91**, the hooks **132** can be housed by being rotated downward, below the bearing **133**. According to this embodiment, the hooks **132** are suppressed from unhooking, and are efficiently housed.

Fourth Embodiment

A fourth embodiment will now be explained. In the explanation below, the elements that are the same as those according to the embodiment described above are assigned with the same reference signs, and explanations thereof will be simplified or omitted.

FIG. **16** is a perspective view of one example of a floodlight **100D** according to this embodiment. FIG. **17** is a plan view of the one example of the floodlight **100D** according to this embodiment. As illustrated in FIGS. **16** and **17**, the floodlight **100D** includes the main-body member **10**, the handle **13** that is coupled to the main-body member **10**, the arm **20** that is coupled to the coupling mechanism **30** provided on the side faces of the main-body member **10**, and that are pivotable about the rotational axis **AX**, the operation device **HD** that is disposed in the coupling mechanism **30** and that is operated to adjust the light emission state of the light emitter unit **12**, and the control device **60**.

Main-Body Member

The main-body member **10** includes the housing **11**, the light emitter unit **12** that is supported by the housing **11**, and

the heat-radiating member 19 that supports the light emitter unit 12. The housing 11 includes the front cover 14, the rear cover 15, and the battery cover 16. The front cover 14 has a plurality of faces that surrounds the light emitter unit 12 and the heat-radiating member 19. The faces include the top face 14a, the bottom face 14b, the right face 14c, and the left face 14d of the front cover 14.

Vents 201 (first vent) are provided to the top face 14a, the bottom face 14b, the right face 14c, and the left face 14d of the front cover 14. At least a part of the heat-radiating member 19 is exposed via the vents 201. The vents 201 connect the internal space of the front cover 14 to the external space.

In the explanation below, the vents 201 that are provided to the top face 14a and the bottom face 14b will be referred to as vertical vents 201A, as appropriate, and the vents 201 provided to the right face 14c and the left face 14d will be referred to as horizontal vents 201B, as appropriate.

The vertical vent 201As are provided along the left-to-right direction. Each of the vertical vents 201A is elongated in the front-and-rear direction. The vertical vents 201A provided on the bottom face 14b are the same as the vertical vents 201A provided to the top face 14a.

The horizontal vents 201B are provided along the up-and-down direction. Each of the horizontal vents 201B is elongated in the front-and-rear direction. The horizontal vents 201B provided on the left face 14d are the same as the horizontal vents 201B provided on the right face 14c.

The light emitter unit 12 includes the light sources 17, and the control board 18 that supports the light sources 17. The control board 18 includes a driving circuit for driving the light sources 17, and a wiring that is connected to the driving circuit. The light sources 17 are disposed on the front face of the control board 18. The light sources 17 are supported on the front face of the control board 18, and emit light forward, with respect to the control board 18.

The heat-radiating member 19 is a heat sink for radiating the heat generated by the light sources 17. The heat-radiating member 19 is made of a material having a higher thermal conductivity than that of which the control board 18 is made. The heat-radiating member 19 is disposed rearward of the control board 18. The heat-radiating member 19 is disposed rearward of the control board 18 in a manner to be in contact with the rear side of the control board 18.

The control board 18 serves as a support member that supports the light sources 17. The heat-radiating member 19 serves as a support member that supports the light sources 17 via the control board 18. In this embodiment, the support members supporting the light sources 17 include the control board 18 and the heat-radiating member 19. The housing 11 of the main-body member 10 supports the support members that support the light sources 17, in the same manner as in the embodiment described above.

Handle

The handle 13 is attached to the main-body member 10. The handle 13 has the pair of base portions 13a that are coupled to the rear cover 15 via the shaft portion 13b, and the holding portion 13c that connects the pair of base portions 13a, in the same manner as in the embodiment described above. The handle 13 is pivotable about the shaft portion 13b. The handle 13 can be moved between the housed position P1 and the standing position P2 (see FIG. 21, for example), by being pivoted about the shaft portion 13b.

With the handle 13 positioned at the housed position P1, the handle 13 restricts the rearward movement of the battery

cover 16 (open direction). With the handle 13 positioned at the standing position P2, a worker can hold the handle 13 smoothly.

Arm

5 The arm 20 is coupled to the coupling mechanism 30 provided on the side faces of the main-body member 10, and is pivotable about the rotational axis AX. The arm 20 includes a first arm 210 that is coupled to the first side face 15R of the main-body member 10 via the first coupling mechanism 31, a second arm 220 that is coupled to the second side face 15L of the main-body member 10 via the second coupling mechanism 32, and a rod 230 that couples the first arm 210 and the second arm 220.

10 The first arm 210 has a base portion 240 that is disposed around the first coupling mechanism 31, and that faces the first side face 15R, an annular portion 242 that is coupled to the base portion 240 and has a grounding portion 250, and a plate portion 244 that is disposed inside the annular portion 242. The base portion 240, the annular portion 242, and the plate portion 244 are integrated.

15 The base portion 240 is coupled to the first side face 15R of the rear cover 15 via the first coupling mechanism 31. The base portion 240 has a plate-like shape, and faces at least a part of the first side face 15R. The base portion 240 is disposed around the first coupling mechanism 31.

20 The annular portion 242 has a first section 242A that extends forward and downward from the front part of the base portion 240 along the first side face 15R, a second section 242B that extends rearward and downward from the rear part of the base portion 240 along the first side face 15R, and a third section 242C that connects the lower end of the first section 242A and the lower end of the second section 242B.

25 The grounding portion 250 is provided on the bottom face of the third section 242C. The grounding portion 250 includes a pad member made of rubber, for example, and two grounding portions 250 are provided on the bottom face of the third section 242C, in the front-and-rear direction.

30 The plate portion 244 is disposed inside the annular portion 242. The plate portion 244 of the first arm 210 has an outer face facing rightward, and an inner face facing leftward. On the inner face of the plate portion 244, a plurality of ribs are provided. A coupler 260 to which the rod 230 is coupled is also provided on the inner face of the plate portion 244.

35 Because the second arm 220 has the same structure as the first arm 210, an explanation of the second arm 220 will be omitted.

40 The rod 230 couples the first arm 210 and the second arm 220. The central axis of the rod 230 is substantially in parallel with the rotational axis AX. The right end of the rod 230 is coupled to the coupler 260 of the first arm 210. The left end of the rod 230 is coupled to the coupler 260 of the

45 second arm 220. In this embodiment, two rods 230 are provided. The first arm 210 and the second arm 220 are coupled to each other via the rods 230. Therefore, the first arm 210 and the second arm 220 are pivotable together about the rotational axis AX.

First Coupling Mechanism and Operation Device

50 The floodlight 100D includes the first coupling mechanism 31 and the operation device HD in the same manner as in the embodiment described above. Because the first coupling mechanism 31 and the operation device HD provided to the floodlight 100D have the same structures as those of the first coupling mechanism 31 and the operation device HD of the floodlight 100A described above, explanations of

the first coupling mechanism 31 and the operation device HD of the floodlight 100D will be omitted.

Second Coupling Mechanism

FIG. 18 is a perspective view of the second coupling mechanism 32 according to the embodiment. As illustrated in FIG. 18, the base portion 240 of the second arm 220 is coupled to the second coupling mechanism 32. The base portion 240 includes the cam 22c. The cam 22c restricts pivoting movements of the arm 20. The cam 22c is provided to the right tip end surface 22d of the base portion 240. FIG. 18 also illustrates the base portion 240 seen from the side of the tip end surface 22d. The cam 22c includes a plurality of protrusions disposed on the tip end surface 22d around the rotational axis AX.

The second coupling mechanism 32 includes the fastening mechanism 35 for fastening the arm 20 to the main-body member 10. The fastening mechanism 35 includes the flange portion 32a, the columnar portion 32b, the cam 32c, the screw portion 32d, and the fastening member 32e. The flange portion 32a is fastened to the second side face 15L. The columnar portion 32b protrudes leftward from the flange portion 32a. The central axis of the columnar portion 32b is coincident with the rotational axis AX.

The cam 32c restricts pivoting movements of the arm 20. The cam 32c is provided on the tip end surface 32f of the columnar portion 32b. The cam 32c has a plurality of protrusions disposed on the tip end surface 32f around the rotational axis AX.

The screw portion 32d protrudes leftward from the tip end surface 32f of the columnar portion 32b. The left end of the screw portion 32d has a male thread.

The fastening member 32e has the screw hole 32g. The screw portion 32d is inserted into the screw hole 32g, and is enmeshed with the screw hole 32g. The fastening member 32e is enmeshed with the screw portion 32d from the left side of the base portion 240. The base portion 240 and the columnar portion 32b are fastened to each other by inserting the left end of the screw portion 32d into the screw hole 32g in the fastening member 32e, and rotating the fastening member 32e in one direction about the rotational axis AX. The fastening between the base portion 240 and the columnar portion 32b is loosened by rotating the fastening member 32e about the rotational axis AX in the other direction.

With the base portion 240 and the columnar portion 32b fastened to each other, the cam 22c of the base portion 240 and the cam 32c of the second coupling mechanism 32 are enmeshed with each other. As a result, the rotations of the base portion 240 about the rotational axis AX are restricted.

With the fastening between the base portion 240 and the columnar portion 32b loosened, the mesh between the cam 22c of the base portion 240 and the cam 32c of the second coupling mechanism 32 is released. As a result, the base portion 240 can be rotated about the rotational axis AX. Furthermore, the position of the arm 20 in the rotating direction about the rotational axis AX can be adjusted.

Heat-Radiating Member

FIG. 19 is a perspective view of the heat-radiating member 19 according to the embodiment. FIG. 19 illustrates the heat-radiating member 19 housed inside the front cover 14, from a viewpoint on the rear side. As illustrated in FIG. 19, the heat-radiating member 19 includes the support panel 19a and fins 19f. The support panel 19a supports the control board 18. The control board 18 is in contact with the support panel 19a.

The fins 19f are supported by the rear face of the support panel 19a, and protrude rearward from the support panel 19a. The fins 19f each have a plate-like shape extending in

the up-and-down direction, and are provided with a space therebetween, in the left-to-right direction.

In this embodiment, the fin 19f is made by bending a metallic plate twice. In the example illustrated in FIG. 19, 30 fins 19f are provided. These 30 fins 19f are formed by bending 15 metallic plates.

Each of the fins 19f has through holes 19h penetrating in the left-to-right direction. The through holes 19h are provided to each of the fins 19f with a space therebetween. In the example illustrated in FIG. 19, seven through holes 19h are provided.

The front cover 14 is disposed in a manner surrounding the light emitter unit 12 and the heat-radiating member 19. The vertical vents 201A are provided on the one side (above) of the fins 19f and on the other side (below) in the up-and-down direction. The horizontal vents 201B are provided on one side (right side) of the fins 19f and on the other side (left side) in the left-to-right direction.

Battery Mounting Unit

FIGS. 20 and 21 are perspective views of the floodlight 100D according to this embodiment seen from the rear side, with the battery cover 16 pivoted rearward (open direction). The main-body member 10 includes the battery mounting unit 70 on which the electric-tool battery 80 is mounted. The battery mounting unit 70 is covered with the battery cover 16. When the electric-tool battery 80 is to be mounted on the battery mounting unit 70 or when the electric-tool battery 80 is to be removed from the battery mounting unit 70, the battery cover 16 is pivoted rearward. FIG. 20 illustrates the battery mounting unit 70 with the electric-tool battery 80 removed. FIG. 21 illustrates the battery mounting unit 70 with the electric-tool battery 80 mounted.

When the battery cover 16 is to be pivoted rearward, the handle 13 is lifted to the standing position P2. By removing the latch 16a after the handle 13 is positioned at the standing position P2, and pivoting the battery cover 16 rearward, the battery mounting unit 70 becomes exposed, as illustrated in FIG. 20. When the battery cover 16 is pivoted forward (in the direction in which the battery cover 16 closes), the latch 16a is moved to the position above the stepped portion 15a, and the battery mounting unit 70 is covered with the battery cover 16.

The rear cover 15 has the second wall 15T. The battery mounting unit 70 is disposed on the second wall 15T. Two battery mounting units 70 are on the second wall 15T. The battery mounting unit 70 has the guide portion 71 for guiding the electric-tool battery 80. The electric-tool battery 80 is mounted on the battery mounting unit 70 while being guided by the guide portion 71. The light emitter unit 12 including the light sources 17, a fan 200, which will be described later, and the control device 60 are driven by the power supplied from the electric-tool battery 80.

Power Supply Cable

FIG. 22 is a perspective view of the floodlight 100D according to this embodiment seen from the rear side, with the connecting portion cover 15g opened. As illustrated in FIG. 22, the connector connecting portion 15p is provided on the rear face 15B of the rear cover 15. The connector 15t of the power supply cable 15r is connected to the connector connecting portion 15p, in the same manner as in the embodiment described above. The connecting portion cover 15g is capable of covering the connector connecting portion 15p.

Fan

FIGS. 23 and 24 are sectional views of the floodlight 100D according to this embodiment. FIG. 25 is a perspective view of the floodlight 100D according to this embodiment.

21

FIG. 23 illustrates a cross section in a direction in parallel with a first predetermined plane including a front-to-rear axis that intersects perpendicularly with rear face of the support panel 19a and an up-and-down axis that is parallel with the rear face of the support panel 19a. FIG. 24 illustrates a cross section in a direction in parallel with a second predetermined plane including the front-to-rear axis that intersects perpendicularly with the rear face of the support panel 19a and a left-to-right axis that is in parallel with the rear face of the support panel 19a. FIG. 25 illustrates the floodlight 100D with a part thereof cut off.

The floodlight 100D includes a fan 200 for generating an air flow on the surface of the heat-radiating member 19 and cooling the light sources 17. The fan 200 is disposed rearward of the heat-radiating member 19, at a position facing the heat-radiating member 19.

The housing 11 has an internal space in which the light emitter unit 12 including the light sources 17 and the control board 18, the heat-radiating member 19, the fan 200, and the electric-tool battery 80 are housed. The internal space of the housing 11 is partitioned into a first internal space SP1 in which the light emitter unit 12 and the heat-radiating member 19 are housed, and a second internal space SP2 in which the fan 200 is disposed. The first internal space SP1 and the second internal space SP2 are partitioned from each other by the first wall 15S of the rear cover 15.

The first internal space SP1 is defined by the front cover 14 and the first wall 15S of the rear cover 15. The second internal space SP2 is defined by the first wall 15S and the second wall 15T of the rear cover 15.

The first wall 15S has an opening 203 that connects the first internal space SP1 and the second internal space SP2. The fan 200 faces the heat-radiating member 19 via the opening 203.

The vents 201 are provided in a manner connecting the first internal space SP1 and the external space of the housing 11. The housing 11 also has vents 202 (second vent) that connect the second internal space SP2 and the external space of the housing 11.

The vents 202 are provided to the rear cover 15. The vents 202 are provided on the left side of the fan 200. The vents 202 are provided along the up-and-down direction. Each of the vents 202 is elongated in the front-and-rear direction. The vents 202 may also be provided on the right side of the fan 200, above the fan 200, or below the fan 200.

The floodlight 100D includes a temperature sensor 204 that detects the temperature of the control board 18. A detection signal from the temperature sensor 204 is output to the control device 60. The detection signal from the temperature sensor 204 indicates the temperature of the control board 18, detected by the temperature sensor 204.

Control Device

FIG. 26 is a functional block diagram illustrating the control device 60 according to the embodiment. The control device 60 includes the input unit 61, the light emission state control unit 62, the storage unit 63, and a fan control unit 67.

The input unit 61 acquires input signals. The input signals acquired by the input unit 61 include a detection signal from the displacement sensor 43, a detection signal from the rotation sensor 53, a remaining charge signal from the electric-tool battery 80, and a detection signal from the temperature sensor 204.

The light emission state control unit 62 controls the light emission state of the light sources 17 based on the amount by which the operation device HD is operated.

The first light emission state control unit 64 controls the light emission state of the light sources 17 based on the

22

detection signal from the displacement sensor 43 having detected the amount by which the switch 41 is operated (the amount of displacement). The light emission state control performed by the first light emission state control unit 64 includes the control for causing the light sources 17 to switch between the on state, the blinking state, and the off state.

The second light emission state control unit 65 controls the light emission state of the light sources 17 based on the detection signal from the rotation sensor 53 having detected the amount by which the dial 51 is operated (the rotational amount). The light emission state control performed by the second light emission state control unit 65 includes the control of illuminance of the light emitted from the light sources 17.

The fan control unit 67 outputs a control signal for controlling the fan 200. The control of the fan 200, the control being performed by the fan control unit 67, includes control for switching the fan 200 to drive and to stop. The control of the fan 200, the control being performed by the fan control unit 67, also includes control of the rotational speed of the fan 200. The fan 200 includes a fan motor, and vanes that are rotated by being driven by the fan motor. The fan control unit 67 controls the fan 200 by outputting a control signal to the fan motor.

The fan control unit 67 controls driving of the fan 200 based on the detection signal from the temperature sensor 204. The storage unit 63 includes a temperature threshold storage unit 68 storing therein a temperature threshold related to the temperature of the control board 18. The temperature threshold is set in advance, and is stored in the temperature threshold storage unit 68. The fan control unit 67 compares the temperature of the control board 18 detected by the temperature sensor 204, with the temperature threshold, and drives the fan 200 when it is determined that the temperature of the control board 18 is equal to or higher than the temperature threshold, and stops the fan 200 when it is determined that the temperature of the control board 18 is lower than the temperature threshold.

The fan control unit 67 may be configured to control the rotational speed of the fan 200 based on the temperature of the control board 18 detected by the temperature sensor 204. The fan control unit 67 may set a higher rotational speed to the fan 200 when the temperature of the control board 18 is higher, and set a lower rotational speed to the fan 200 when the temperature of the control board 18 is lower.

The fan control unit 67 may be configured to control driving of the fan 200 based on the amount by which the operation device HD is operated. For example, based on the detection signal from the displacement sensor 43 having detected the amount by which the switch 41 is operated (the amount of displacement), the fan control unit 67 may drive the fan 200 when it is determined that the light sources 17 are in the on state, and stop the fan 200 when it is determined that the light sources 17 are in the off state. Furthermore, based on the detection signal from the rotation sensor 53 having detected the amount by which the dial 51 is operated (the rotational amount), the fan control unit 67 may increase the rotational speed of the fan 200 when the illuminance of the light emitted from the light sources 17 is higher, and decrease the rotational speed of the fan 200 when the illuminance of the light emitted from the light sources 17 is lower.

The fan control unit 67 may be configured to control driving of the fan 200 based on the remaining charge signal output from the electric-tool battery 80. For example, the fan control unit 67 may drive the fan 200 when it is determined

that the temperature of the control board 18 is equal to or higher than the temperature threshold, and that the remaining charge in the electric-tool battery 80 is equal to or higher than a remaining charge threshold, and stop the fan 200 when it is determined that the temperature of the control board 18 is equal to or higher than the temperature threshold but the remaining charge in the electric-tool battery 80 is lower than the remaining charge threshold.

Furthermore, the fan control unit 67 may be configured to set a higher rotational speed to the fan 200 when the remaining charge in the electric-tool battery 80 is higher, and to set a lower rotational speed to the fan 200 when the remaining charge in the electric-tool battery 80 is lower, while the temperature of the control board 18 is equal to or higher than the temperature threshold.

Effects

Effects of the fan 200 according to the embodiment will now be explained. FIG. 27 is a schematic illustrating effects of the fan 200 according to the embodiment, and is a schematic sectional view of a part of the floodlight 100D. FIG. 27(A) illustrates a cross section in a direction in parallel with the second predetermined plane including the front-to-rear axis that intersects perpendicularly with the rear face of the support panel 19a, and the left-to-right axis that is in parallel with rear face of the support panel 19a. FIG. 27(B) is a cross section in a direction in parallel with the first predetermined plane including the front-to-rear axis that intersects perpendicularly with the rear face of the support panel 19a and the up-and-down axis that is in parallel with the rear face of the support panel 19a.

When the light sources 17 are driven, the light sources 17 become heated. As the light sources 17 are heated, the temperature of the control board 18 increases. The temperature of the control board 18 is detected by the temperature sensor 204. The temperature sensor 204 outputs a detection signal indicating the temperature of the control board 18, to the control device 60.

The input unit 61 acquires the detection signal from the temperature sensor 204. The fan control unit 67 compares the temperature of the control board 18 detected by the temperature sensor 204, with the temperature threshold stored in the temperature threshold storage unit 68, and starts driving the fan 200 if it is determined that the temperature of the control board 18 is equal to or higher than the temperature threshold.

In this embodiment, the fan 200 supplies a gas to the heat-radiating member 19. When the fan 200 is driven, the gas in the external space of the housing 11 enters the second internal space SP2 via the vents 202. The fan 200 supplies the gas to the heat-radiating member 19 via the opening 203 on the first wall 15S.

As the fan 200 is driven, at least a part of the gas in the second internal space SP2 enters the first internal space SP1 via the opening 203. As the fan 200 is driven, an air flow is generated on at least a part of the surface of the heat-radiating member 19. The gas brought into contact with the surface of the heat-radiating member 19 deprives the heat from the heat-radiating member 19.

As illustrated in FIG. 27(A), the fins 19f are disposed along the left-to-right direction. In this embodiment, the through holes 19h are provided to each of the fins 19f. Therefore, the gas supplied to the heat-radiating member 19 by the fan 200 can flow smoothly in the left-to-right direction via the through holes 19h.

The horizontal vents 201B are provided on the one side (right side) of the fins 19f, and on the other side (left side), in the left-to-right direction. The gas having flowed in the left-to-right direction via the through hole 19h is allowed to flow out to the external space of the housing 11, via the horizontal vents 201B.

As illustrated in FIG. 27(B), the fin 19f has a plate-like shape extending in the up-and-down direction. Therefore, the gas supplied to the heat-radiating member 19 by the fan 200 can flow smoothly in the up-and-down directions, along the surfaces of the fins 19f.

The vertical vents 201A are provided on one side of (above) the fins 19f, and on the other side (below), in the up-and-down direction. The gas having flowed in the up-and-down directions along the surfaces of the fins 19f can flow out to the external space of the housing 11 via the vertical vents 201A.

Advantageous Effects

As explained above, according to this embodiment, the fan 200 generates an air flow on the surface of the heat-radiating member 19 supporting the light sources 17. The gas flowing in contact with the surface of the heat-radiating member 19 deprives heat from the heat-radiating member 19. Therefore, excessive heating of the light sources 17 is suppressed.

The light sources 17 are supported on the front face of the control board 18, and emit light forward, with respect to the control board 18. The fan 200 is disposed rearward of the heat-radiating member 19, at a position facing the heat-radiating member 19. Because the fan 200 is not disposed on the light path of the light emitted from the light sources 17, the floodlight 100D can illuminate an object to be illuminated, smoothly. Furthermore, because the fan 200 is disposed at a position facing the heat-radiating member 19, gas can be supplied sufficiently to the heat-radiating member 19.

The internal space of the housing 11 is partitioned by the first wall 15S into the first internal space SP1 and the second internal space SP2. The light sources 17, the control board 18, and the heat-radiating member 19 are disposed inside the first internal space SP1, and the fan 200 is disposed inside the second internal space SP2. The first internal space SP1 and the second internal space SP2 are connected to each other only via the opening 203. Because the first internal space SP1 and the second internal space SP2 are partitioned, the entry of a foreign substance, having entered the second internal space SP2, into the first internal space SP1 is suppressed, for example. Furthermore, by sealing the first internal space SP1 with a seal member, the entry of a foreign substance into the first internal space SP1 is suppressed effectively.

The second internal space SP2 in which the fan 200 is disposed is connected to the external space of the housing 11 via the vents 202. With this configuration, when the fan 200 is driven, the gas in the external space flows into the second internal space SP2 via the vents 202. Therefore, the fan 200 can supply the gas smoothly into the heat-radiating member 19.

The first internal space SP1 in which the light sources 17, the control board 18, and the heat-radiating member 19 are disposed is connected to the external space of the housing 11 via the vents 201. With this configuration, the gas having deprived the heat from the heat-radiating member 19 can flow out to the external space of the housing 11 via the vents 201. Because the gas heated by being brought into contact with the heat-radiating member 19 is discharged smoothly to

the external space of the housing 11 via the vents 201, a reduction in the efficiency at which the light sources 17 are cooled is suppressed.

The fin 19f has a plate-like shape extending in the up-and-down direction. Therefore, the gas supplied to the heat-radiating member 19 by the fan 200 can flow smoothly in the up-and-down directions along the surfaces of the fins 19f. The vertical vents 201A are provided above and below the fins 19f. The gas having flowed in the up-and-down directions along the surfaces of the fins 19f can smoothly flow out to the external space of the housing 11 via the vertical vents 201A.

The fins 19f have the through holes 19h penetrating in the left-to-right direction. Therefore, the gas supplied by the fan 200 to the heat-radiating member 19 can flow smoothly in the left-to-right directions via the through holes 19h. The horizontal vents 201B are provided on the right side and the left side of the fins 19f. The gas having flowed in the left-to-right directions via the through holes 19h can smoothly flow out to the external space of the housing 11 via the horizontal vents 201B.

In this embodiment, the temperature of the control board 18 is detected by the temperature sensor 204, and driving of the fan 200 is controlled based on the detection signal from the temperature sensor 204. Because the fan 200 is not driven when the light sources 17 are not excessively heated, and when it is not necessary to cool the light sources 17, the power consumption by the fan 200 is suppressed.

Driving of the fan 200 may be controlled based on the amount by which the operation device HD for adjusting the light emission state of the light sources 17 is operated. Depending on the light emission state of the light sources 17, it is sometimes not necessary to cool the light sources 17, because the light sources 17 are not excessively heated. By not to drive the fan 200 in circumstances in which it is not necessary to cool the light sources 17, the power consumption by the fan 200 is suppressed.

Even in circumstances in which it is necessary to cool the light sources 17, the power consumption of the electric-tool battery 80 can be suppressed by reducing the rotational speed of the fan 200, or stopping the fan 200 when the remaining charge of the electric-tool battery 80 is low.

In this embodiment, the fan 200 is explained to supply gas to the heat-radiating member 19. The fan 200 may also be configured to recover gas from the heat-radiating member 19. In other words, the fan 200 may suction the gas around the heat-radiating member 19. By causing the fan 200 to suction gas, an air flow is generated on the surface of the heat-radiating member 19, so that the light sources 17 are cooled thereby.

In this embodiment, the heat-radiating member 19 may be omitted. Even in a configuration in which the heat-radiating member 19 is omitted, by causing the fan 200 to generate an air flow on the surface of the control board 18, the light sources 17 can be cooled effectively.

Another Embodiment

Explained in the embodiment described above is an example in which the switch mechanism 40 and the dial mechanism 50 are disposed in the first coupling mechanism 31 of the coupling mechanism 30, but the embodiment is not limited thereto. For example, one of the switch mechanism 40 and the dial mechanism 50 may be disposed in the first

coupling mechanism 31, and the other may be disposed in the second coupling mechanism 32.

The invention claimed is:

1. A floodlight comprising:
a housing having an internal space;
a wall that partitions the internal space into a first internal
space and a second internal space, and has an opening
that connects the first internal space and the second
internal space;
one or more first vents that connect the first internal space
to an external space;
a second vent that connects the second internal space to
the external space;
a support member in the first internal space;
a plurality of fins that protrude rearward from the support
member, the fins each having a plate-like shape extend-
ing in a first direction on a predetermined plane that is
in parallel with a rear face of the support member, the
fins being arranged in a second direction on the pre-
dicted plane that perpendicularly intersects with
the first direction;
a light source in the first internal space and supported by
a front face of the support member, the light source
emitting light forward with respect to the support
member; and
a fan in the second internal space and that cools the light
source by generating an air flow on a surface of the
support member, the fan being disposed rearward of the
support member, at a position facing the support mem-
ber via the opening.

2. The floodlight according to claim 1, wherein
the support member includes
a control board that has a driving circuit for driving the
light source and supports the light source, and
a heat-radiating member that is in contact with the
control board, and
the fan generates an air flow on a surface of the heat-
radiating member.

3. The floodlight according to claim 2, wherein
the light source is disposed on a front face of the control
board,
the heat-radiating member is disposed rearward of the
control board, in a manner to be in contact with the
control board, and
the fan is disposed at a position facing the heat-radiating
member.

4. The floodlight according to claim 3, wherein
the heat-radiating member includes a support panel that is
in contact with the control board,
the fins are supported on a rear face of the support panel
and protrudes rearward from the support panel,
each of the fins has a through hole that penetrates in the
second direction, and
the first vents are provided on one side and on another side
of the fins in the first direction, and are provided on one
side and on another side of the fins in the second
direction.

5. The floodlight according to claim 1, further comprising:
a temperature sensor that detects a temperature of the
support member; and
a fan control unit that controls driving of the fan based on
a detection signal from the temperature sensor.

6. The floodlight according to claim 5, wherein the fan
control unit drives the fan when the temperature of the
support member is equal to or higher than a temperature
threshold, and stops the fan when the temperature of the
support member is lower than the temperature threshold.

7. The floodlight according to claim 1, further comprising:
an operation device that is operated to adjust a light
emission state of the light source;

31

22. The floodlight according to claim 21, wherein the first side face is a top face of the housing, and the second side face is a bottom face of the housing.
23. The floodlight according to claim 22, wherein the housing includes a third side face and a fourth side face, 5 the third side face is a left face of the housing, the fourth side face is a right face of the housing, the vents includes a third vent provided on the third side face, and a fourth vent provided on the fourth side face, 10 and the heat-radiating member is exposed via the first vent, the second vent, the third vent, and the fourth vent.
24. The floodlight according to claim 23, wherein the heat-radiating member includes a support panel that supports the control board, 15 the fins protrude from the support panel, and the fins each have a through hole.

32

25. The floodlight according to claim 24, wherein the fins each have a plate-like shape extending in an up-and-down direction, and are provided with a space therebetween in a left-and-right direction, the though holes penetrate through the fins in the left-and-right direction, the first vent is provided on an upper side of the fins, the second vent is provided on a lower side of the fins, the third vent is provided on a left side of the fins, and the fourth vent is provided on a right side of the fins.
26. The floodlight according to claim 25, wherein the internal space of the housing is partitioned by a wall into a first internal space in which the light emitter unit and the heat-radiating member are housed, and a second internal space in which the fan is housed, the wall has an opening that connects the first internal space and the second internal space, and the fan faces the heat-radiating member via the opening.
